INVENTOR:
Wells S. Fleming.

By Horace Barnes
ATTORNEY.

UNITED STATES PATENT OFFICE

WELLS S. FLEMING, OF PORTLAND, OREGON

SURFACE DRAIN

Application filed July 22, 1926. Serial No. 124,186.

This invention relates to improvements in floor drain fittings for shower baths and the like.

The object of my invention is the provision of a floor drain of simple and practical construction which is adjustable for installation in floors of various thicknesses and to which a sheet of waterproofing material may be connected in watertight condition without the 10 employment of bolts or screws to make a watertight joint to prevent the leakage of water past the fitting and thereby protect the walls and ceilings in rooms below in the building from damage.

15 Other objects and advantages of my invention, and objects relating to details of construction and arrangement of parts, will be readily apparent in the course of the detailed description to follow.

20 The accompanying drawings illustrate, by way of example, one form in which my invention may be embodied, wherein:

Fig. 1 is a vertical section of the floor drain embodying my invention and set up in operative position; the section being taken on the line 1—1 of Fig. 2.

Fig. 2 is a horizontal section of the same on line 2—2 of Fig. 1.

Referring to said views, the reference 30 numeral 1 indicates the cylindrical body of my improved floor drain having a bore 2 extending vertically therethrough. Said bore is provided with screw-threads 3 with which the end of a waste or drain pipe, not shown, 35 may be connected. At its upper end said bore is counterbored and provided with screw-threads, as at 5.

A circular flange 6 extends in substantially horizontal directions with a relatively slight 40 upward angle to afford drainage toward the bore 2, said flange being recessed at its upper face, as at 7.

A sheet of waterproofing material 8, such as sheet lead or tarred paper, apertured about 45 the bore 2, is laid upon said flange and is clamped thereon in watertight condition by means of an annular spider-plate 10 bearing upon said waterproof material adjacent the outer edge of said recess, as will be more fully 50 explained hereafter.

Said spider-plate is provided with a plurality of evenly spaced integral arms 11 extending upwardly and inwardly and integrally connected to an annular collar 12 whose central opening is disposed in substantially vertical alignment with the counterbore 5 of the body.

55 A tubular hub 13 extends axially through the central opening of the collar 12 and is screw-threaded at its lower extremity to engage the screw-threads of the counterbore 5 and has its inner tubular face 15 in substantial alignment with the bore 2. Said hub is formed with a head having a circular portion 16 arranged to bear upon the collar 12 of the spider-plate and an hexagonal upward portion 17 adapted to receive a wrench. The interior tubular surface of said hub is provided with screw-threads 18 at its upper portion, and therebelow the hub is formed with a plurality of vertically elongated slots 20 in spaced relation about its circumference which are positioned to extend from a little below the plane of the recess 7 upwardly therefrom to a point adjacent the screw-threads 18.

70 75 A drain section 21 includes a tubular portion 22 and a funnel shaped upper end 23. The tubular portion 22 is provided with external screw-threads interfiting with the screw-threads 18 of the hub, whereby the drain section may be adjusted to the desired elevation. The upper end of the funnel portion 23 is provided with a grille-plate 25 designed to be adjusted to the level of the floor in which the fitting is set.

80 85 To insure that the spider-plate 10 will not move in rotary directions when the hub portion 16 is screwed down thereupon, I provide an aperture 26 in said spider-plate within which an integral stud 27, extending upwardly from the flange 6, protrudes.

90 95 The drain body 1 is set upon the subfloor 28 of the building in which the fitting is installed, and the waterproof sheet 8 is laid over the flange 6 as described. The spider-plate 10 is then positioned thereover, and the tubular hub 13 is extended into the counterbore 5 of the bore and the screw-threads thereon engaged to bring the head portion 16 to bear with pressure upon the collar 12, which 100

pressure will be communicated to the plate 10 and clamp the waterproof sheet firmly upon the flange 6 in watertight condition.

The drain section 21 may then be inserted 5 within the tubular hub and adjusted to the height to which the superficial floor 30 is to be leveled. Said floor 30 may be composed of plastic or other suitable material and overlie and enclose the parts of the drain fitting in 10 permanent condition.

Having described my invention, what I 15 claim is:

1. A floor drain consisting of a tubular body having a laterally extending flange and a threaded central bore, a spider-like annular plate seating on said flange, the flange and said plate being adapted to have a sheet of water-proofing material interposed between them, and a tubular nut extending through 20 said plate, threaded into said body-bore, said nut provided with a circumferential flange engaging with said plate, thereby to press said plate firmly upon the water-proofing sheet placed upon said flange.

2. A floor drain consisting of a tubular body having a laterally extending flange and a threaded central bore, a spider-like annular plate seating on said flange, the flange and said plate being adapted to have a sheet of water-proofing material interposed between them, and a tubular nut extending through 25 said plate, threaded into said body-bore, said nut provided with a circumferential flange engaging with said plate, thereby to press said plate firmly upon the water-proofing sheet placed upon said flange, and said tubular nut, provided with spaced circumferential openings at the level of said plate.

3. A floor drain consisting of a tubular body having a laterally extending cupped circumferential flange and a threaded central bore, a spider-like annular plate seating on said flange, the flange and said plate being adapted to have a sheet of water-proofing material interposed between them, and a tubular nut having external threads at its lower end and internal threads at its upper end extending through said plate, threaded into said body-bore, said nut provided with a circumferential flange engaging with said plate, thereby to press said plate firmly upon the water-proofing sheet placed upon said flange, and a drain section threaded into said nut, adjustable to various elevations above said 50 plate.

4. A floor drain consisting of a tubular body having a laterally extending cupped circumferential flange and a threaded central bore, a spider-like annular plate seating on 55 said flange, the flange and said plate being adapted to have a sheet of water-proofing material interposed between them, and a tubular nut extending through said plate, threaded into said body-bore, said nut provided with a circumferential flange engaging

with said plate, thereby to press said plate firmly upon the water-proofing sheet placed upon said flange, said tubular nut, provided with spaced circumferential openings at the level of said plate, and means to lock said plate on said flange against circumferential movement.

5. A floor drain consisting of a tubular body having a laterally extending cupped circumferential flange and a threaded central bore, a spider-like annular plate seating on said flange, the flange and said plate being adapted to have a sheet of water-proofing material interposed between them, and a tubular nut having external threads at its lower end and internal threads at its upper end extending through said plate, threaded into said body-bore, said nut provided with a circumferential flange engaging with said plate, thereby to press said plate firmly upon the water-proofing sheet placed upon said flange, said tubular nut, provided with spaced circumferential openings at the level of said plate, means to lock said plate on said flange against circumferential movement, and a drain section threaded into said nut, adjustable to various elevations above said plate.

6. A floor drain consisting of a tubular body having a laterally extending cupped circumferential flange and a threaded central bore, a spider-like annular plate seating on said flange, the flange and said plate being adapted to have a sheet of water-proofing material interposed between them, and a tubular nut extending through said plate, threaded into said body-bore, said nut provided with a circumferential flange engaging with said plate, thereby to press said plate firmly upon the water-proofing sheet placed upon said flange, and means to lock said plate on said flange against circumferential movement.
